UNITED STATES PATENT OFFICE

WILLIAM C. FLOYD, OF HAWKINSVILLE, GEORGIA, ASSIGNOR OF ONE-THIRD TO D. A. SIMPSON, OF HAWKINSVILLE, GEORGIA

AUTOGUN

Application filed October 7, 1931. Serial No. 567,503.

This invention aims to provide an automatic pistol which may have the usual trigger guard and grip of the old time revolver. Another object of the invention is to provide 5 novel means for cocking the hammer, by the backward movement of a slide, which operates independently of the barrel, the barrel being fixed against longitudinal movement. Another object of the invention is to provide 10 a novel three-piece construction in the trigger, the trigger operator and the hammer. A further object of the invention is to improve the construction of the magazine which carries the cartridges. A still further object 15 of the invention is to improve the safety mechanism.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing 30 from the spirit of the invention.

In the accompanying drawings:—

Figure 1 shows, in side elevation, a device constructed in accordance with the invention;

Figure 2 is a vertical longitudinal section, 35 with the parts in firing position;

Figure 3 is a view similar to Figure 2 but showing the parts as they will appear when in loading position;

Figure 4 is a longitudinal section on the line 4—4 of Figure 1;

Figure 5 is a bottom plan view of the slide;

Figure 6 is a top plan view of the frame of the pistol, with the slide removed;

Figure 7 is a side elevation of the barrel;

Figure 8 is a longitudinal section taken approximately on the line 8—8 of Figure 2;

Figure 9 is a transverse vertical section taken approximately on the line 9—9 of Figure 3;

Figure 10 is a side elevation of one of the safety slides;

Figure 11 is a side elevation of another of the safety slides;

Figure 12 is a side elevation showing a modification.

The firearm forming the subject matter of this application comprises a frame 1 supplied with a forwardly prolonged extension 2. In the upper part of the extension 2, at the forward end thereof, there is a longitudinal groove 3, to be seen in Figure 6. Across the groove 3, at the rear end thereof, extend transverse ribs 4 (Figures 6 and 2), which are formed integrally with the frame 1. There is an opening 5 through the frame of the pistol, and this opening is located to the rear of the ribs 4, as Figures 6 and 2 will show. The frame 1 has an upstanding lug 6 (Figures 3 and 6) located at the rear end of the opening 5. In the frame 1, to the rear of the lug 6, there is a slot 7 (Figures 6, 2 and 3). The frame 1 and its extension 2 are provided with guide grooves 8 on their opposite sides, and these grooves are shown in Figure 9. Below the slot 7, a compartment 9 is formed in the frame 1, and the compartment 9 communicates with a compartment 10 formed in a grip 11, the grip being fashioned very much like the grip of an old time revolver, as distinguished from the grip of a modern automatic pistol, one of the objects of the invention being to provide an automatic pistol which has a grip of the kind mentioned. The frame 1 has a vertical receiver 12 for the magazine (hereinafter described) the receiver being located below the opening 5 in the frame 1. A trigger guard 14 is carried by the frame 1 and extends between the grip 11 and the receiver 12.

A barrel is shown in detail in Figure 7 of the drawings, and is marked by the numeral 15. It has an enlargement 16 at its rear end, and this enlargement forms a shoulder 17. In the bottom of the enlargement 16 there are transverse grooves 18. The barrel 15 is received in the groove 3 of the extension 2 of the frame 1 (Figures 2 and 6), and the transverse grooves 18 of the barrel 15 receive the transverse ribs 4 of the frame 1. The

barrel 15, thus, in cooperation with parts hereinafter described, is held against longitudinal movement. In the rear end of the enlargement 16 of the barrel 15, at one side thereof, there is a notch 19, for the shell ejector, which will be described hereinafter.

A slide 20 is mounted for longitudinal reciprocation on the frame 1, the slide being trough-shaped in cross section, as Figure 10 9 will show. The slide 20 is provided with longitudinal ribs 21 (Figures 5 and 9) and these ribs slide in the guide grooves 8 of the frame 1. It can be seen in the Figures 5 and 4 that, at its forward end, the slide 20 has a longitudinal groove 22 which receives the barrel 15. Behind the groove 22, the slide 20 has a thickened part 23. The slide 20 carries the rear sight 24 and the front sight 25. The numeral 26 designates 15 an L-shaped guide, including a transverse part and a longitudinal part, to be seen clearly in Figures 3 and 2 of the drawings. The slide 20 is provided at its forward end (Figure 5) with a recess 27 in which 20 the transverse part of the guide 26 fits, the guide 26 being held upon the slide 20 by means of a securing element 28, the guide constituting, to all intents and purposes, a part of the slide 20. The forward extension 25 30 of the frame 1 is slidably received in the longitudinal part of the guide 26. A compression spring 29 is located in the groove 22 of the slide 20 (Figure 5) and in the corresponding groove 3 of the extension 2 of the frame 1. The compression spring surrounds the barrel 15, one end of the spring abutting against transverse part of the guide 26, and the opposite end of the spring abutting 35 against the shoulder 17 that is formed 40 by the enlargement 16 of the barrel 15. The barrel 15 is held against longitudinal movement by the ribs 4 on the extension 2 of the frame 1, and by the corresponding shaped 45 grooves 18 of the barrel, and, therefore, the function of the spring 29, abutting against the transverse part of the guide 26 which is 50 secured at 28 to the slide 20, is to advance the slide. The slide 20 has a hole 30 on one side, shown in Figures 1 and 9. In the hole 30 55 operates a spring actuated shell ejector 31 (Figures 1 and 4) carried by the slide, and adapted to cooperate with the notch 19 (Figure 7) that is formed in the enlargement 16 of the barrel 15. In the bottom of the thickened part 23 of the slide 20 there is a longitudinal recess 32 (Figures 5, 2 and 3). The said part 23 of the slide 20 is supplied with a longitudinal groove 33 which opens 60 through the shoulder 79 existing in the slide 20 at the back end of the groove or chamber 22. The groove 33 is adapted for the reception of the lug 6 of Figures 3 and 6, which, it is to be recalled, upstands from the frame 65 of the arm.

65 A firing pin 34 is mounted for longitudinal

reciprocation in the slide 20 and the movement of the firing pin is limited by a cross pin 35 in the slide 20. The firing pin 34 is retracted by a compression spring 36, disclosed in Figures 2 and 3 of the drawings.

The hammer is marked by the numeral 37 and is adapted to cooperate with the firing pin 34. The hammer 37 extends into the compartment 9 of the frame 1, and is mounted to swing on a pivot element 38, carried by the frame 1, and holding in place a closure plate 39 (Figure 1) for the frame compartment 9 (Figure 3). In the lower portion of its forward edge, the hammer 37 has a full-cock notch 40, and a safety notch 140. The hammer 37 is swung upwardly and forwardly, to firing position, by any suitable means, such as a plunger 41, the upper end of which is pivoted at 42 formed upon the hammer 37. The plunger 41 is located in the compartment 10 of the grip 11, and slides in a transverse partition 44 carried by the grip 11. The plunger 41 has an abutment 45. A compression spring 46 surrounds the plunger 41, one end of the spring engaging the abutment 45, and the other end of the spring engaging the partition 44. The function of the spring 46 is to move the plunger 41 upwardly, thereby swinging the hammer 37 from the position of Figure 3 to the position of Figure 2. In the lower end of the plunger 41 there is another abutment 145. A compression spring 146 surrounds the lower end of the plunger 41, one end of the spring engaging the abutment 145, and the opposite end of the spring 146 engaging the partition 44. The spring 146 is weaker than the spring 46, and the function of the spring 146 is to pull the hammer back to safety position, or half-cock, after the arm has been fired. The spring 146 acts counter to the spring 46, but the spring 146 is so much weaker than the spring 46 that the efficiency of the spring 46 as a means for moving the hammer 37 to firing position is not impaired enough to cut any figure.

A trigger 47 extends within the trigger guard 14, and the trigger extends into the compartment 9 of the frame 1. The trigger 47 is mounted to swing on a pivot element 48, secured in the frame 1, and aiding in holding the closure plate 39 in place. The trigger 47 carries a rearwardly extended sear 49, adapted to cooperate with the notches 49 and 140 of the hammer 37. In the rear part of the sear 49 there is an elongated guide slot 50, receiving a cross screw 51, mounted in the frame 1 and in the closure plate 39. The numeral 52 designates an angular sear operator disposed in the compartment 9. The sear operator 52 is mounted for swinging movement on a pivot element 53 carried by the frame 1 and the closure plate 39. One end of the sear operator 52 extends upwardly through the slot 7 in the frame 1, into the path of the shoulder 78 which exists in the slide 20, at

the forward end of the recess 32 in the slide, the said recess receiving the upper, forward end of the sear operator 52. The rear, lower end of the sear operator 52 bears on the upper end of the sear 49, under the impulse of a compression spring 54, which is interposed between the frame 1 and the rear end of the sear.

A removable magazine 55 is insertable into the receiver 12 and is held in the receiver by a transverse, spring actuated latch 56 (Figures 3 and 9) mounted to reciprocate in the forward portion of the trigger guard 14. On its rear edge, the magazine 55 has a rib 58, in which a keeper 57 is formed, the keeper being adapted to receive the latch 56, as Figure 3 will show. The latch 56 has a transverse notch 59 (Figure 9). When the latch 56 is in the outwardly projected position of Figure 9, the latch is engaged in the keeper 57 of the rib 58 on the magazine 55, and the magazine cannot be removed. By shoving the latch 56 inwardly, however, the notch 59 in the latch is brought opposite to the rib 58 on the magazine 55, and, then, the magazine 55 can be removed. The magazine 55 extends upwardly into the opening 5 of the frame 1. The magazine 55 is provided at its lower end with a forwardly extended tail piece 60, against which presses a spring actuated plunger 61, mounted to slide in the receiver 12, the function of the plunger 61 being to start the magazine 55 downwardly, when the latch 56 has been pushed inwardly to release the magazine 55 for downward movement. A follower 62 is mounted for reciprocation in the magazine 55, and is advanced by a compression spring 63 located in the magazine.

The shells 64, which are advanced, one after another, by the follower 62 and the spring 63, are stored in the magazine 55.

A safety slide 65 is mounted for longitudinal reciprocation in a groove in the frame 1, and this safety slide is accessible from without the arm, as Figures 6 and 8 will show. The slide under discussion is shown in detail in Figure 11. It is held in place, for limited longitudinal movement, by means of a stop screw 66 or the like, mounted in the frame 1 near to the rear end thereof and shown in Figures 8 and 6. The slide 65 reciprocates behind a guide 67, secured to one side of the frame 1, within the compartment 9. The slide 65 carries a laterally extended and downwardly prolonged shoulder 68, which may be in the form of a block, secured to the slide. In the forward end of the slide 65 there is an elongated slot 69 (Figure 11) receiving a securing element 70, such as a headed screw, mounted in the guide 67.

Above the safety slide 65 is located a second slide 71, shown in detail in Figure 10, and appearing clearly in Figures 2 and 3. The safety slide 71 has an elongated slot 72, receiving a securing element 73, mounted in

the frame 1. At its forward end, the second safety slide 71 has a depending bevelled head 74, operating through an opening 75 (Figure 3) in the frame 1. The bevelled head 74 of the slide 71 is adapted to cooperate with the magazine 55, in a way which will be pointed out hereinafter. The slide 71 extends backwardly above the guide 67. A compression spring 76 is interposed between the rear end of the slide 71 and a portion of the frame 1, and is adapted to advance the slide, when the magazine 55 is removed. The slide 71 has a reduced, depending finger 77 which is adapted to be advanced above the rear, upper end of the sear 49, when the second slide 71 moves forwardly from the position of Figure 3. In a similar way, the shoulder 68 on the safety slide 65 is adapted to engage above the rear, upper end of the sear 49, when the said slide is moved backwardly from the position of Figure 3.

Let it be presumed that the parts are in the positions of Figure 2, the pistol having been fired. The shell 64 in the rear end of the barrel 15 carries the slide 20 backwardly, as the said shell is exploded, the spring 29 being compressed. As the slide 20 moves backwardly, the shell is stopped by contact with the lug 6 of Figure 3, and the ejector 31 of Figure 4 throws the shell outwardly through the opening 30 (Figure 1) of the slide 20. As the slide 20 moves backwardly, another shell is advanced by the follower 62, into the position of Figure 3, when the slide 20 has moved back far enough to permit this to be done, the shell being received, as in Figure 3, in the back part of the groove 22 of the slide, in front of the shoulder 79.

As the slide 20 moves backwardly, it engages the hammer 37 and swings the hammer 37 downwardly on its pivotal mounting 38, the plunger 41 being carried downwardly, and the spring 46 being compressed. As the slide 20 moves rearwardly, the shoulder 78 (Figure 3) of the slide and engages the upper end of the sear operator 52, and tilts the sear operator on its fulcrum 53, the rear end of the sear operator 52 swinging downwardly, and carrying the rear end of the sear 49 downwardly, the upper end of the sear being engaged in the full-cock notch 40 of the hammer 37, the spring 54 acting, also, to carry the rear end of the sear operator 52 downwardly, as aforesaid. The trigger 47 is swung forwardly, and the arm now is cocked, as in Figure 3, with the slide 20 still retracted.

The spring 29 has been compressed, and this spring reacts, and moves the slide 20 forwardly, to the position of Figure 2, with the shoulder 79 behind the shell 64 which is in place in the barrel 15, the hammer 37 remaining in the cocked position of Figure 2.

The operator, in order to discharge the arm, tilts the trigger 47 rearwardly, thereby raising the rear end of the sear 49 and dis-

engaging the rear end of the sear from the notch 40 in the trigger 37, the rear end of the sear operator 52 being raised, the forward, upper end of the sear operator being lowered in the slot 7 of the frame 1, and the spring 54 being compressed. The hammer 37, responding to the movement of the plunger 41, under the actuation of the spring 46, passes to the position of Figure 2 and strikes the firing pin 34, the firing pin being advanced to discharge the shell which is in the barrel. The spring 146 reacts to swing the hammer 37 back until the rear end of the sear 49 engages in the safety notch 140 of the hammer.

When the magazine 55 is introduced into the receiver 12, the upper end of the magazine cooperates with the bevelled head 74 of the second safety slide 71, and moves the said slide rearwardly, against the action of the spring 76. This operation carries the finger 77 (Figure 10) of the safety slide 71 to the rear of the upper end of the sear 49, as shown in dotted line in Figure 2, and the trigger 47 may be pulled, so far as any interference on the part of the safety slide 71 is concerned. When, however, the magazine 55 is removed from the receiver 12, then the spring 76 advances the slide 71 until the finger 77 of Figure 10 is above the upper, rear end of the sear 49, and the trigger 47 cannot be pulled. The result is that it is impossible to shoot the pistol with the magazine 55 partly in place. The arm cannot be discharged until the magazine 55 has been restored to the position of Figure 2, so as to engage the bevelled head 74 of the slide 71 and to carry the slide rearwardly, out of engagement with the rear, upper end of the sear 49.

The slide 65 is under the control of an operator. When the slide 65 is advanced to the position of Figure 2, the shoulder 68 of Figures 11 and 2 is in front of the upper end of the sear 49, and to one side of the sear. The trigger 47, therefore, may be pulled at will, but when the operator draws the slide 65 backwardly, by means of the laterally projecting portion thereof, shown in Figure 8, then the shoulder 68 of the slide is above the rear, upper end of the sear 49, and the trigger 47 cannot be pulled.

In view of what has been stated hereinbefore, it will be clear that the pistol has two safety mechanisms, one of which is under the control of an operator, and is designated by the numeral 65, the other of which is under the control of the magazine 55, and is designated by the numeral 71.

The device forming the subject matter of this application has many advantages, one of which is simplicity of construction over other automatic pistols. It is characterized by a high degree of safety, owing to the presence of the slides 71 and 65. It will be observed that throughout the entire arm,

simple, inexpensive coil springs, such as the springs 46, 54 and 36 are used. The arm cannot be fired when the magazine is wholly or partly withdrawn, accidents due to the presumption that there is no cartridge in the barrel after withdrawing the magazine 55, being made impossible. The sear 49 is formed in one piece with the trigger 47 and operates without springs. The working mechanism immediately associated with the trigger 47, embraces but three pieces, namely, the sear 49, the hammer 37, and the sear operator 52. The arm may be operated with great rapidity, notwithstanding its simplicity.

In Figure 12, the parts hereinbefore described have been designated by numerals previously used, with the suffix "a". The modification consists in making the magazine 55a longer than the magazine 55 of Figure 2, and the arm, in the form of Figure 12, becomes a two handed machine pistol, it being possible to hold the grip 11a in one hand, and the downwardly projecting part of the magazine 55a in the other hand.

What is claimed is:

1. A pistol comprising a frame, a hammer movably mounted on the frame, a barrel fixed upon the frame, a slide mounted to reciprocate on the frame, the slide forming an abutment for a cartridge in the barrel, the slide being rearwardly movable, responsive to the recoil of an exploding cartridge, to move the slide rearwardly, the slide engaging the hammer, as the slide moves rearwardly, thereby to cock the hammer, spring means for advancing the slide, firing means carried by the slide and located between the hammer and the barrel, a trigger movably mounted upon the frame, and carrying fixed connected therewith, a sear which engages the hammer, to hold the hammer cocked, and a sear operator movably mounted on the frame and engaging the sear, to cause the sear to engage the hammer and hold the hammer cocked, the sear operator extending into the path of the slide, whereby, when the slide moves rearwardly, to cock the hammer, the slide will act, through the instrumentality of the sear operator, to engage the sear with the hammer.

2. A pistol comprising a frame, a hammer movably mounted on the frame, a barrel fixed upon the frame, a slide mounted to reciprocate on the frame, the slide forming an abutment for a cartridge in the barrel, the slide being rearwardly movable, responsive to the recoil of an exploding cartridge, to move the slide rearwardly, the slide engaging the hammer, as the slide moves rearwardly, thereby to cock the hammer, spring means for advancing the slide, firing means carried by the slide and located between the hammer and the barrel, a trigger movably mounted upon the frame, and carrying, fixedly connected therewith, a sear which engages the hammer, to hold the

- hammer cocked, a sear operator movably mounted on the frame and engaging the sear, to cause the sear to engage the hammer and hold the hammer cocked, the sear operator extending into the path of the slide, whereby, when the slide moves rearwardly, to cock the hammer, the slide will act, through the instrumentality of the sear operator, to engage the sear with the hammer, a magazine and means associated therewith for carrying a cartridge from the magazine to a position in front of the slide, when the slide is retracted, the slide advancing the cartridge into the barrel, when the slide is advanced, means for mounting the magazine movably in the frame, and a safety member movably mounted on the frame and engaging the sear, to hold the sear engaged with the hammer, when the hammer is cocked, the safety member extending into the path of the magazine, as the magazine is introduced into the frame, whereby the magazine will move the safety member out of engagement with the sear.
3. A pistol comprising a frame, a hammer movably mounted on the frame, a barrel fixed upon the frame, a slide mounted to reciprocate on the frame, the slide forming an abutment for a cartridge in the barrel, the slide being rearwardly movable, responsive to the recoil of an exploding cartridge, to move the slide rearwardly, the slide engaging the hammer, as the slide moves rearwardly, thereby to cock the hammer, spring means for advancing the slide, firing means carried by the slide and located between the hammer and the barrel, a trigger movably mounted upon the frame; cooperating elements comprising a sear fixedly connected to the trigger, and a sear operator movably mounted on the frame; the sear engaging the hammer to hold the hammer cocked, the sear operator engaging the sear to cause the sear to engage the hammer and to hold the hammer cocked, the sear operator extending into the path of the slide, whereby, when the slide moves rearwardly, to cock the hammer, the slide will act, through the instrumentality of the sear operator, to engage the sear with the hammer, and a safety member under the control of an operator and movably mounted on the frame, the safety member being engageable with one of said cooperating elements, to hold the sear engaged with the hammer, when the hammer is cocked.
4. A pistol comprising a frame, a hammer movably mounted on the frame, a barrel fixed upon the frame, a slide mounted to reciprocate on the frame, the slide forming an abutment for a cartridge in the barrel, the slide being rearwardly movable, responsive to the recoil of an exploding cartridge, to move the slide rearwardly, the slide engaging the hammer, as the slide moves rearwardly, thereby to cock the hammer, spring means for advancing the slide, firing means carried by the slide and located between the hammer and the barrel, a trigger movably mounted upon the frame; cooperating elements comprising a sear fixedly connected to the trigger, and a sear operator movably mounted on the frame; the sear engaging the hammer to hold the hammer cocked, the sear operator engaging the sear to cause the sear to engage the hammer and to hold the hammer cocked, the sear operator extending into the path of the slide, whereby, when the slide moves rearwardly, to cock the hammer, the slide will act, through the instrumentality of the sear operator, to engage the sear with the hammer, and a safety member under the control of an operator and movably mounted on the frame, the safety member being engageable with one of said cooperating elements, to hold the sear engaged with the hammer, when the hammer is cocked.
5. A pistol comprising a frame, a hammer movably mounted on the frame, a barrel fixed upon the frame, a slide mounted to reciprocate on the frame, the slide forming an abutment for a cartridge in the barrel, the slide being rearwardly movable, responsive to the recoil of an exploding cartridge, to move the slide rearwardly, the slide engaging the hammer, as the slide moves rearwardly, thereby to cock the hammer, spring means for advancing the slide, firing means carried by the slide and located between the hammer and the barrel, a trigger movably mounted upon the frame; cooperating elements comprising a sear fixedly connected to the trigger, and a sear operator movably mounted on the frame; the sear engaging the hammer to hold the hammer cocked, the sear operator engaging the sear to cause the sear to engage the hammer and to hold the hammer cocked, the sear operator extending into the path of the slide, whereby, when the slide moves rearwardly, to cock the hammer, the slide will act, through the instrumentality of the sear operator, to engage the sear with the hammer, and a safety member under the control of an operator and movably mounted on the frame, the safety member being engageable with one of said cooperating elements, to hold the sear engaged with the hammer, when the hammer is cocked.

ing the cartridge into the barrel, when the slide is advanced, means for mounting the magazine movably on the frame, and a second safety member movably mounted on the frame and engaging one of said cooperating elements, to hold the sear engaged with the hammer, when the hammer is cocked, the second safety member extending into the path of the magazine, as the magazine is introduced into the frame, whereby the magazine will move the second safety member out of engagement with that one of said cooperating elements which the safety member engages.

6. A pistol comprising a frame, a hammer movably mounted on the frame, a barrel fixed upon the frame, a slide mounted to reciprocate on the frame, the slide forming an abutment for a cartridge in the barrel, the slide being rearwardly movable, responsive to the recoil of an exploding cartridge, to move the slide rearwardly, the slide engaging the hammer, as the slide moves rearwardly, thereby to cock the hammer, spring means for advancing the slide, firing means carried by the slide and located between the hammer and the barrel, a trigger movably mounted upon the frame; cooperating elements comprising a sear fixedly connected to the trigger, and a sear operator movably mounted on the frame, the sear engaging the hammer to hold the hammer cocked, the sear operator engaging the sear to cause the sear to engage the hammer and to hold the hammer cocked, the sear operator extending into the path of the slide, whereby, when the slide moves rearwardly, to cock the hammer, the slide will act, through the instrumentality of the sear operator, to engage the sear with the hammer, a magazine and means associated therewith for carrying a cartridge from the magazine to a position in front of the slide, when the slide is retracted, the slide advancing the cartridge into the barrel, when the slide is advanced, means for mounting the magazine movably on the frame, a safety member movably mounted on the frame and engaging one of said cooperating elements, to hold the sear engaged with the hammer, when the hammer is cocked, the safety member extending into the path of the magazine, as the magazine is introduced into the frame, whereby the magazine will move the safety member out of engagement with said one of said cooperating elements, a second safety member under the control of an operator and movably mounted on the frame, the second safety member being engageable with one of said cooperating elements, to hold the sear engaged with the hammer, when the hammer is cocked.

7. A pistol comprising a frame having a grip, a hammer movably mounted on the frame, a barrel fixed upon the frame, a slide mounted to reciprocate on the frame, the slide

forming an abutment for a cartridge in the barrel, the slide being rearwardly movable, responsive to the recoil of an exploding cartridge, to move the slide rearwardly, the slide engaging the hammer, as the slide moves rearwardly, thereby to cock the hammer, spring means for advancing the slide, firing means carried by the slide and located between the hammer and the barrel, a plunger engaged pivotally at its upper end with the hammer and extended downwardly into the grip, a member carried by the grip, and wherein the plunger can swing and also slide longitudinally, and springs about the plunger, the springs having their inner ends in abutment with said member, their outer ends being in abutment with the plunger, one of said springs being an actuating spring for the plunger and the hammer, and the other of said springs being a rebound spring which operates on the plunger to move the hammer to safety position.

In testimony that I claim the foregoing as my own, I have hereto affixed my signature.

WILLIAM C. FLOYD.
